UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

MINING APPARATUS.

Application filed October 25, 1922. Serial No. 596,747.

My invention relates to mining machines and one of its objects is the provision of improved and efficient means for drilling holes through a wall or a pillar of coal between adjacent mine chambers to provide "break-throughs" for the purpose of ventilation. More particularly it is the object of the present invention to provide improved and efficient means for boring holes at intervals through a partition in a mine chamber to provide openings between such chambers for the purpose of ventilating the space where mining operations are being carried on.

A further object of the invention is the provision of mechanism for boring holes in a mine wall combined with a coal mining and loading machine with provision in common with the latter and the boring mechanism for taking care of the cuttings produced by the mining mechanism as well as by the boring mechanism.

Another object of the invention is the provision of mining mechanism including ventilating apparatus therefor and means for forming passageways through which the ventilating mechanism may operate in proximity to the mining mechanism.

Other objects of the invention will appear hereinafter, the novel features and combinations being set forth in the appended claims.

Referring to the accompanying drawings,

Fig. 1 is an elevational view of a mining and loading machine with boring mechanism and ventilating mechanism mounted thereon;

Fig. 2 is a plan view of the structure shown in Fig. 1;

Fig. 3 is a sectional plan view of two mine chambers to illustrate diagrammatically the operation of my invention;

Fig. 4 is an enlarged rear elevation of the boring mechanism with the supporting framework broken away from the framework of the mining and loading machine;

Fig. 5 is an end elevational view of Fig. 4;

Fig. 6 is a sectional plan view of a detail construction; and

Fig. 7 is a sectional elevation of the mechanism for feeding the drill into the mine wall.

As shown in Figs. 1 and 2, the base frame 8 is provided with spaced-apart upright standards 9 adapted to be anchored by means of roof jacks 10. Pivoted to the upper ends of the standards 9 is a main

frame 11 to which is pivoted a screw-threaded rod 12 on which is mounted a wheel 13 for engaging the arm 14 to vary the inclination of the main frame 11, together with the parts mounted thereon.

At the forward end of the main frame 11 is a loop chain core-cutter 15 adapted to be swung on an upright axis while pulling into the mine wall the belt 16, as shown in Fig. 2. After the core has been cut a pull is exerted on the rear end of the belt 16 to break the core material against the drum 17, as shown in dotted lines in Fig. 2. By continued pull on the belt 16 the cut-out material is delivered to the conveyer 18 for delivery to the rear end 19 of the mining and loading machine.

A motor 20 is geared to the shaft 21 on which are mounted the worms 22, 23 and 24. The worm 22 meshes with the worm gear 25 for operating the rope drum 26 so that the rope 27 may be pulled to effect feeding of the loop chain core-cutter 15. The worm 24 meshes with the worm gear 28 so as to operate the winding drum 29 on which the belt 16 is wound. As shown in Fig. 1, the worm gear 28 is connected to the drum 29 by means of the clutch 30, whereas the rope drum 26 is connected to the worm gear 25 by means of the clutch 31.

The worm 23 meshes with the worm gear 32 at the upper end of the shaft 33. By means of a clutch 34 the worm gear 32 is connected to the shaft 33 to drive the latter so as to transmit motion to the sprocket at the lower end of the shaft 33. This sprocket is connected by means of the sprocket chain 35 to another sprocket which is located at the rear end 19 of the main frame of the mining and loading machine. The last-named sprocket is connected by a vertical shaft 36 to the sprocket 37 which meshes with the main conveyer chain 18. The latter extends around the sprocket at the forward portion of the main frame so as to drive the gear 38 which transmits power to the chain cutter 15.

The conveyer chain 18 is provided with lateral extending flights 39 which move along a trough 40, the forward end of which is inclined, as shown at 41 in Fig. 1, so as to provide an inclined surface, arcuate in plan, for the cuttings from the chain cutter to move over into the trough 40. The chain cutter 15 is preferably so operated as

to have the emerging run at the lower side and thus cause the cuttings to be moved over the surface 41 into the trough 40 where such cuttings will be gathered by the flights 39 and moved toward the rear end of the machine, together with the coal which is dislodged from the mine wall.

The type of mining and loading machine may be similar in construction and operation 10 to that disclosed in my Patent No. 1,325,031, granted December 16, 1919, for an improvement in mining machines, although other types of machines may be used so far as the use of drilling mechanism and ventilating 15 apparatus in combination with a mining and loading machine, is concerned. The present application is a continuation in part of my co-pending application, Serial No. 296,867, filed May 13, 1919, as a division of Serial No. 20 764,487, filed April 30, 1913, loading machine, since in said divisional application boring mechanism is shown mounted on a mining and loading machine for producing "break-through passages" in the manner 25 illustrated in Fig. 3 of the accompanying drawings. I prefer, however, to mount the boring apparatus on the mining and loading machine in such a manner as to deliver the cuttings from the drill to the conveyer which 30 takes care of the cuttings from the chain kerf-cutter 15, as well as taking care of the material which is dislodged by the mining mechanism.

The drilling mechanism for boring the 35 holes 42 shown in Fig. 3 comprises a drill 43 mounted in a semi-circular trough 44 having a cylindrical outer end 45, as shown in Figs. 2 and 4. The trough 44 is provided on its 40 under side with an inverted T-shaped head 46 (Fig. 5) to form a sliding fit with the spaced-apart grooves or guides 47 on the pedestal 48. By reason of the dovetail connection between the trough 44 and the pedestal 48 the trough may be adjustably positioned 45 relative to the framework of the mining and loading machine so as to make a close fit with the mine wall, as illustrated in Fig. 3. This will enable the cuttings produced by the drill 43 to enter the trough 44 and on account of the spiral blades of the 50 drill, the latter acts as a spiral conveyer for conducting the drill cuttings away from the mine wall along the trough 44 out of the end 49, from which the drill cuttings are deposited into the path of the flights 39 of the 55 conveyer 18.

After the trough 44 has been moved 60 against the mine wall, as shown in Fig. 3, it may be secured in adjusted position by means of the set screw which is operated by the wheel 50.

The lower end of the pedestal 48 is provided with a disc 51 which fits into a circular groove in the bracket 52 and therefore the 65 trough 44 may be adjusted angularly on an

upright axis which is located at the center of the disc 51. After such arcuate adjustment has been made the drill, together with the trough 44, may be secured in adjusted position by means of the set screw 53 which is operated by the wheel 54.

The bracket 52 is secured to the plate 55 which is provided with a slot 56 so that by means of cap screws 57 extending through the plate 58 the drill may be adjusted in position longitudinally of the main frame of the mining and loading machine. The plate 58 is secured to the main frame, as indicated at 59 in Fig. 2, and at 60 is secured a bracket 61 through which extends a screw-threaded 65 rod 62 having a wheel 63 at one end, the rod 62 being threaded through the bracket 52. Therefore, by loosening the cap screws 57 and operating the wheel 63 the bracket 52, together with the drill and the trough, may be moved along the plate 58 for adjustment longitudinally thereof. When in adjusted position the cap screws 57 are each operated to securely fasten the plate 55 to the frame 58.

In order to rotate the drill an electric motor 64 mounted on a bracket 65 is connected by a train of gearing 66 to the shaft 67 which is journaled in the bearing 68 mounted on the bracket 65. The shaft 67 carries a socket 69 into which fits the squared end 70 of the drill 43. The bracket 65 is provided with spaced-apart inner grooves 71, 71 which fit over the guide flanges 72, 72 at the sides of the trough 44 so that the motor 64, the drill 43, and the power transmission mechanism between the motor 64 and the drill 43 may all move as a unit bodily along the trough 44 while being guided by the lateral flanges 72 of the trough.

In order to feed the drill one of the flanges 72 is provided with rack teeth 73 with which meshes a pinion 74 at the lower end of the vertical shaft 75 which is journaled in the bearings 76 and 77, as shown in Fig. 7. The bearing 77 is connected directly to the bracket 65 and the bearing 76 is connected to the casing 78 which in turn is rigidly connected to the bracket 65. It will thus be seen that the bracket 65 constitutes a housing and a supporting frame for the mechanism which rotates the drill and also the mechanism which feeds it.

As shown in Fig. 7, the motor shaft 79 is provided with a worm 80 which meshes with a worm gear 81 on a shaft 82 mounted in the bearing 83 attached to the floor of the casing 78. Loosely mounted on the shaft 82 are spaced-apart bevel gears 84 and 85 between which is a double clutch 86 which may be operated by means of a lever 87. The bevel gear 85 is somewhat larger in diameter than the bevel gear 84. The bevel gear 85 meshes with a horizontal bevel gear 88 and the bevel gear 84 meshes with another hori- 125 130

horizontal bevel gear 89, the bevel gears 88 and 89 being concentric with each other and both mounted on the upper end of the shaft 75. When it is desired to feed the drill into the coal while the latter is being rotated the clutch 86, as viewed in Fig. 7, is shifted to the left so as to transmit motion from the motor shaft 79 to the bevel gear 84 and thence through the bevel gear 89 to the vertical shaft 75 to rotate the pinion 74. Since the latter meshes with the rack 73 and this rack remains stationary the drill will be fed slowly into the mine vein. When it is desired to retract the drill the clutch 86 is shifted toward the right, as viewed in Fig. 7, to cause the larger bevel gear 85 to rotate the bevel gear 88 and thus transmit a quick rotatable motion to the drill while the latter is being rotated and while the spiral convolutions of the drill are acting as a conveyer to continue to move the cuttings from the trough 44 through the opening 49 to the conveyer 18. It should be understood that while the drill is being fed into a mine vein it acts as a spiral conveyer to move the cuttings from the mine wall along the trough 41 toward the opening 49, and when the drill is retracted such cuttings as may remain in the trough 44 are removed through the opening 49 by the continued rotation of the drill, the latter always being rotated in the same direction. A single motor 64 is connected to both the feeding mechanism and the driving mechanism and therefore the drill will be rotated in the same direction whenever it is fed into the mine wall or retracted therefrom.

As shown in Figs. 1, 2 and 3, an air suction fan 90 is mounted on the horizontal plate 58 which is connected at 59 to the frame of the mining and loading machine. Directly connected to the suction fan 90 is an electric motor 91. The suction fan or blower 90 is connected by the pipe 92 to the flexible coupling 93 which in turn is connected to the elbow 94, the latter fitting into an opening 42 in the mine wall or partition 95. When the suction fan 90 operates it draws the dust-laden air in the room where the mining operation is taking place through the intake opening 96 and blows it through the opening 42 into the next adjacent room, as shown in Fig. 3.

The holes 42 in the mine wall 95 may be produced by the boring tool 43 which is connected to be operated by the electric motor 64, mounted as above described.

While the loop chain core-cutter is being operated and producing slack or coal dust which floats in the air the blower 90 is constantly taking such dust-laden air and blowing it into the next adjacent room. The electrically operated blower is therefore the means of ventilating the mine and of putting the coal dust into a place where it will not interfere with the mining machine or with the operator. At the same time that the room in which the mining operation is being carried on is ventilated, the boring tool 43 is producing a new opening through the pillar or partition 95. The new opening 70 through the wall 95 may be located ahead of the opening through which the blower is sending the dust-laden air, any suitable or convenient distance, preferably a considerable distance so that the opening in service 75 may serve the machine for a considerable portion of advance travel. It may, however, be located a distance about substantially equal to the travel that the forward portion of the mining machine takes when moved to 80 a new cutting position. Therefore, when the rear portion of a mining machine is moved forward the elbow 94 will be in proper position to ventilate through the opening which has just been made through the mine wall. 85 The opening which has just been left by the elbow 94 can then be closed by means of a plug 97, as shown in Fig. 3. Therefore, at the time that the cutting operation of the mining machine is taking place all of 90 the openings back of the ventilator are plugged up and the opening produced by the drill 43 is still incomplete. Therefore the only communication between the mining machine room and the next adjacent room is 95 through the opening 42 through which the blower is being operated, as shown in Fig. 3.

When it is desired to operate the entire machine shown in the accompanying drawings, it is first brought into the position 100 shown in Fig. 3 and anchored by means of the roof jacks 10. Then by operating the wheel 13 the cutter may be adjusted to various elevations so as to make approximately three cuts across the mine wall for dislodging the material in comparatively large lumps and deliver it to the conveyer 18, as shown in Fig. 2. When the electric motor 20 operates it serves as a source of power for driving the loop chain core-cutter 15 as well 110 as feeding it and also serves as a source of power for removing the material to the conveyer and for operating the conveyer. The cuttings produced by the kerf-cutter 15 are delivered over the inclined surface 41 to the 115 trough 40 so that the conveyer 18 may deliver such cuttings to the rear end of the mining and loading machine. Simultaneously with the operation of the mining and loading machine the blower 90 is operating 120 to take the dust-laden air from the mining machine and deliver it through the opening 42 into the adjacent chamber. This intake opening 96 is preferably at the rear end of the machine where the large blocks of coal, 125 together with the cuttings, are being delivered to a mine car. Simultaneously with the operating of the mining machine and the operation of the ventilating apparatus the drill 43 is being operated by the electric 130

motor 64 to drill another hole through the mine wall, and while this drilling is taking place the cuttings from the drill are being delivered to the conveyer which is in operation. It will thus be seen that drilling is effected at the same time that the mining operations are carried on and the cuttings from the drill are taken care of by the same conveyer which takes care of the cuttings from the kerf-cutter. As soon as the mining operations are completed everything will be in readiness for movement of the mining and loading machine as a whole to a new location because by that time a hole has been drilled through the mine wall and the cuttings have all been removed. As soon as the mining machine is moved to its new location and anchored the ventilating apparatus may be connected to the hole which has been last drilled and a plug 97 used to close the opening to which the ventilating apparatus was previously connected.

Obviously those skilled in the art may make various changes in the details and arrangement of parts without departing from the spirit and scope of the invention as defined by the claims hereto appended and I wish therefore not to be restricted to the precise construction herein disclosed.

Having thus fully disclosed an embodiment of my invention, what I desire to secure by Letters Patent of the United States is:

1. The combination with a mining machine, of a blower, means for operating said blower to force air from the mining machine room into the next adjacent room, a boring tool mounted on said mining machine, and means for operating said boring tool to bore a hole through the mine wall into the next adjacent room for connection to the blower thereto when the machine is moved forward to a new position.

2. The combination with a mining machine comprising cutting apparatus and adapted to be moved forward to new operating positions step by step, of a boring device mounted on said mining machine, means for operating said boring device to produce an opening through the mine wall into the next adjacent room, a blower mounted on said mining machine, means for operating said blower, and a connection between said blower and an opening in the mine wall.

3. The combination with a supporting frame adapted to be located in a coal mine chamber adjacent a coal pillar, of a traveling conveyer extending along said frame in a general horizontal direction, means in position on said frame for producing a cross-cut in such pillar of coal, and mechanism for directing coal from said cross-cut forming means to said conveyer near the delivery end of the latter.

4. The combination with a supporting

frame, of a traveling conveyer extending longitudinally thereof in a horizontal direction, a drill having spiral conveyer blades mounted in an elevated position to produce a cross-cut in a pillar of coal adjacent said frame, and a trough associated with said blades to cause the latter to act as a spiral conveyer for removing cuttings produced by said drill and deliver such cuttings to said conveyer.

5. The combination with a mining machine, of a drill mounted thereon, means for operating said drill simultaneously with the operation of said mining machine, and a blower mounted on said mining machine and connected to a hole previously drilled by said drill and adapted to be operated simultaneously with the operation of said mining machine and with the operation of said drill.

6. The combination with a mining and loading machine comprising kerf-cutting mechanism and a conveyer extending to the rear end of the machine, of a drill extending transversely of the machine in position to drill a hole in the mine vein at one side of the machine, means for directing cuttings from said kerf-cutting mechanism to said conveyer mechanism, means for simultaneously directing cuttings from said drill to said conveyer, and suction apparatus mounted on the machine with an intake opening near the delivery end of said conveyer.

7. In combination, a supporting frame, a drill guide frame mounted on said supporting frame for adjustment relatively thereto into position where such guide frame abuts against an upright mine wall, a trough for receiving the cuttings from said drill, and means for operating said drill including feeding movement thereof along said guide frame while the latter remains in such position abutting against the mine wall and while the cuttings are received by said trough.

8. In mining apparatus, the combination with a supporting frame, of a guide frame comprising a trough for movement relatively to said supporting frame into position to abut against the mine wall, a drill mounted on said guide frame and having spiral conveyer blades extending along said trough, and means for operating said drill including feeding movement thereof relatively to said guide frame while the latter is being held stationary and connected to said supporting frame and while said spiral blades rotate in said trough.

9. In mining apparatus, the combination with a supporting frame, of a guide frame mounted for movement relatively thereto into position to abut against the mine wall, said guide frame comprising a trough, a drill mounted on said guide frame in position to direct cuttings into said trough, a tubular extension from said guide frame in position

to engage the mine wall, means for holding the guide frame and said tubular extension in stationary position with said tubular extension contacting with the mine wall, and 5 means for operating said drill including feeding movement thereof along said guide frame to said tubular extension while the cuttings are received by said trough.

10. In combination, a portable supporting frame, an auxiliary frame mounted thereon in predetermined relation thereto for adjustment longitudinally thereof along a mine wall, a tertiary frame mounted on said supplemental frame for arcuate adjustment relatively thereto on an upright axis, guiding mechanism mounted on said tertiary frame for adjustment relatively thereto longitudinally of said guiding mechanism, a drill mounted on said guiding mechanism, 20 and means for operating said drill including feeding movement thereof along said guiding mechanism while said frames and said guiding mechanism are held in adjusted stationary positions on said supporting frame 25 and while the latter remains stationary.

11. In combination, a portable supporting frame, a drill, means for mounting said drill on said frame for adjustment along said frame transversely of said drill, guiding 30 mechanism for the drill, and means for operating the drill including feeding movement thereof longitudinally of said guiding mechanism while said mounting means and said guiding mechanism remain fixed to said frame and while the latter remains stationary.

12. In mining apparatus, the combination with loading apparatus comprising a traveling conveyer, of a semi-cylindrical trough having an opening in its rear portion for 40 passage therethrough by gravity to said conveyer of material conveyed along said trough, a spiral bladed drill mounted in said trough, a rack extending along one side of said trough, a frame guided along the lateral edges of said trough, means for supporting said drill in position to form an opening in an upright face of a mine vein above the floor level of the mine chamber, and means 45 mounted on said frame for operating said drill including feed thereof along said rack while said opening remains in delivery relation to said conveyer.

13. In mining apparatus, the combination 55 with a loading machine comprising a supporting frame with a conveyer thereon, of a drill, means for guiding said drill for operation on an upright mine wall adjacent said frame to produce a mine ventilating cross-cut in a coal pillar, said guiding means being adapted also to receive the cuttings and deliver the same to said conveyer, means for operating said drill including feeding mechanism comprising a longitudinal rack, means 60 for effecting a retraction of the drill at a

higher speed than the feed thereof, and means for mounting said guiding means on said supporting frame in compact relation therewith by extending entirely across said frame above said conveyer and permitting 70 substantially the whole length of the drill to penetrate the mine wall while said frame remains stationary adjacent the same and while said guiding means remains in delivery relation to said conveyer.

14. The combination with a mining machine comprising a supporting frame, of a blower mounted on the rear portion of said supporting frame and connected to a "break-through" for directing dust-laden air from 80 the mining machine into an adjacent mine chamber, and drilling mechanism mounted on said supporting frame in advance of said blower in position to produce another "break-through" into the adjacent chamber 85 during the operation of the mining machine.

15. The combination with a mining and loading machine comprising kerf-cutting mechanism and a conveyer, of ventilating apparatus mounted on the mining and loading machine and connected through a "break-through" to an adjacent chamber, an adjustable guide frame having a trough adapted to abut against a mine wall at one side of the mining and loading machine in 95 advance of the ventilating mechanism, drilling mechanism comprising a spiral blade in said trough for producing another "break-through" into the adjacent chamber 100 while delivering the cuttings from the drilling mechanism along said trough through an opening in the rear portion thereof to said conveyer, and means for operating said drilling mechanism simultaneously with the operation of the mining and loading machine and simultaneously with the operation 105 of said ventilating mechanism.

16. In loading apparatus, the combination with a conveyer adapted to load coal into a mine car, of a laterally swingable frame 110 supported above one end of said conveyer, a motor supported by said frame, a drill operatively connected to said motor and adapted to drill a hole in an upright mine wall adjacent said conveyer, and means for conveying the cuttings of the drill to said conveyer.

17. In mining apparatus, the combination with a supporting frame, of a traveling flight 115 conveyer thereon, a drill, means for supporting said drill for adjustment longitudinally of said frame and also pivotally on an upright axis and also transversely of said frame, means for operating said drill, and mechanism for delivering the cuttings from 120 said drill to said conveyer.

18. The combination with a combined mining and loading machine adapted to be moved forward step by step to new mining 125 positions and comprising a frame with a 130

conveyer thereon, means mounted on said frame in position to operate from one side thereof to form a mine ventilating opening in a pillar of coal adjacent said frame, means for operating said opening forming means, mechanism for delivering to said conveyer the coal dislodged by said opening forming means, a blower mounted on the rear portion of said frame, means connecting said blower to a previously forming opening in the pillar of coal, and means for operating said blower to force air from the mining and loading machine room through the coal pillar into the next adjacent room while said mining and loading machine is being operated and while said opening forming means is operating to produce another forwardly spaced opening in said pillar and while the coal dislodged by said opening forming means is being delivered to said conveyer.

19. In mining apparatus, the combination with a supporting frame, of a conveyer mounted thereon, a blower mounted on said frame, means for forming a mine ventilating opening in a pillar of coal adjacent said frame, mechanism connecting said blower to such ventilating opening after being formed in the pillar, means for operating said blower to force air into the next adjacent room through the opening to which said blower is connected, and means for operating said opening forming means laterally from said frame in a position spaced ahead of the previously formed opening.

20. The combination with a supporting frame, of a conveyer thereon, means on said frame in position to act laterally therefrom

adjacent said conveyer for forming a mine ventilating opening in a pillar of coal adjacent said frame, a blower mounted on said frame, means for operating said blower, and means for connecting the blower to a previously formed opening spaced back from the operating position of said opening forming means.

21. The combination with a combined mining and loading machine, of means mounted thereon in position to operate laterally therefrom to form a mine ventilating opening in a pillar adjacent said machine, means for operating said opening forming means simultaneously with the operation of said machine, and a blower mounted on said machine and connected to an opening previously formed by said opening forming means to be operated simultaneously with the operation of said machine and with the operation of said opening forming means.

22. In mining apparatus, the combination with a supporting frame, of a conveyer thereon, a blower mounted on the rear portion of said frame and connected to a "break-through" for directing dust-laden air from said conveyer into the next adjacent room, and means mounted on said frame in advance of said blower in position to produce another "break-through" into said next adjacent room during the operation of said conveyer and during the operation of said blower.

In testimony whereof I have signed my name to this specification on this 20th day of October, A. D. 1922.

EDMUND C. MORGAN.
